R. L. QUASS

MEASURED SERVICE TELEPHONE SYSTEM

Filed June 6, 1922

Inventor:
Ralph L. Quass.

by Webb, Atty.

UNITED STATES PATENT OFFICE.

RALPH L. QUASS, OF HAWTHORNE, NEW JERSEY, ASSIGNOR TO WESTERN ELECTRIC COMPANY, INCORPORATED, OF NEW YORK, N. Y., A CORPORATION OF NEW YORK.

MEASURED-SERVICE TELEPHONE SYSTEM.

Application filed June 6, 1922. Serial No. 566,287.

To all whom it may concern:

Be it known that I, RALPH L. QUASS, a citizen of the United States, residing at Hawthorne, in the county of Passaic, State of New Jersey, have invented certain new and useful Improvements in Measured-Service Telephone Systems, of which the following is a full, clear, concise, and exact description.

10 This invention relates to automatic telephone systems and more specifically to a controlling circuit for a measured service device or meter in systems of this type.

The invention is an improvement over the system of Patent No. 1,379,068, issued May 24, 1921, to John Wicks. In the system of that patent an electrically polarized relay is provided in the trunk circuit which relay in its inert condition holds operated a slow-to-release relay which at a back contact maintains the meter circuit open until the called party answers. As the circuit is intended to operate this polarized relay will not remain operated on momentary reversals 25 of the current flow caused by ringing back over the trunk in revertive calls long enough to release the slow relay to cause it to close the meter circuit, but when the current in the trunk is permanently reversed by the 30 response of the called party, the slow relay circuit is opened long enough to release it to close the meter circuit. However, due to the fact that the polarized relay is electrically polarized, said relay will operate if the ringing current is cut off on that part 35 of the wave which assists the polarizing winding of the relay and the relay will remain operated by the polarized winding. Thus the slow relay will be released long enough to close the meter circuit and falsely record a call.

One of the features of this invention is the provision of a biased permanently polarized relay instead of an electrically polarized relay to control the meter circuit. The slow relay is held operated to open the meter circuit by a circuit including a normal contact of this permanently polarized relay. Thus even though the ringing current stops on that part of the wave which causes the current in the polarized relay to

operate it, this does not cause a false operation of the meter because the instant the ringing current is cut off the armature of the polarized relay is restored to its normal 55 position, reclosing the circuit of the slow relay before it can release to close the meter circuit.

Another feature of the invention relates to an improved means for operating the secondary line switch in a system wherein meters are employed, and resides in a circuit arrangement which obviates the possibility of the primary line switch releasing prematurely.

In accordance with this feature of the invention the circuit for the operating winding of the secondary line switch includes a winding of the meter and contacts closed by the primary line switch in seizing the secondary line switch, whereby the secondary line switch immediately operates to cause ground to be placed on the release conductor leading back to the primary line switch to hold it set after the line relay which operates the primary line switch in the first instance, releases. The meter magnet is marginal and does not operate in the operating circuit for the secondary line switch. However, upon the response of the called 75 party an operating circuit for said meter magnet is closed to cause the call to be charged.

Referring to the drawing, comprising but a single sheet only so much of an automatic 85 telephone system is shown as is necessary to comprehend the invention. Reference should be made to the said Wicks patent for the detailed operation of the circuits with which the invention is not directly 90 concerned.

It is thought that the invention will be most readily understood from a detailed description of the operation of the circuits.

When a subscriber at substation A removes his receiver to initiate a call a circuit is closed for the line relay 2 of the primary line switch C in series with the calling line. Relay 2 closes the circuit of the pull-in winding 3 to attract the plunger and close 95 the springs 4, 5, 6 and 7 in contact to extend the line circuit to a secondary line 100

2
switch D in the well known manner as described in said Wicks patent. The relay 2 is disconnected from the line by the operation of the pull-in winding 3 but being slow-to-release maintains the circuit of winding 3 closed until ground is supplied to the holding winding 8 over the release trunk 14 from secondary line switch D. As soon as springs 7 close contact a circuit is closed for the pull-in winding of the secondary line switch, as follows: left winding of meter 9, springs 7, conductor 40, contacts 33, 100, 34 of polarized relay 11, release conductor 14, conductor 35, contact 101 of slow-to-release relay 10, conductor 36, pull-in winding 12 of the switch D, contact 19, slow-to-release relay 13 to battery.

The left winding of the meter magnet 9 is of such low resistance that it will not operate in this circuit. The pull-in winding 12 and slow release relay 13, however, operate in this circuit. The slow-to-release high resistance relay 10 operates in a circuit which branches off at point 37 from the circuit previously traced. Relay 10 at the continuity contact 38 maintains the circuit for the pull-in winding 12 and relay 13 after it is broken at contact 101. The left winding of the meter magnet 9 is marginal as stated and cannot operate in the circuits so far traced. Relay 13 energizes to connect ground to the release conductor 14 connected to holding winding 8 of the operated primary line switch C. Winding 12 operates to plunge the secondary line switch and close in contact the pairs of springs 15, 16, 17, 18 to extend the calling line to a first selector E. The winding 12 in operating opens contact 19 and connects itself in series with high resistance winding 20 to the grounded right armature of slow relay 10. Before slow relay 13 releases due to the opening of contact 19 a holding ground is applied to release conductor 21 from the selector E as shown and described in detail in said Wicks patent to hold the switches C and D set, and to cause the seized selector E to test busy.

The selector E is now set under control of the dial 23 to pick out an idle connector H, whereupon the connector is set on the called line. The selector E and connector H are not shown in detail since they may be of the type shown and described in the said Wicks patent.

When the telephone is removed from the hook at substation B relay 24 operates, reversing the direction of the current flow in the calling line and trunk, this circuit including relay 25 and polarized relay 11.

The polarized relay 11 operates due to this reversal and shifts its armature to open the circuit of slow relay 10, which in retracting its right armature substitutes ground from the trunk release wire 21 over

conductor 35 and contact 101 for the ground on said armature, to hold the secondary line switch D set. In retracting its inner left armature it closes an operating circuit for the meter as follows: battery, low resistance 70 39, inner left armature and normal contact of relay 10, contact 27, conductor 40, contact 7, conductor 41, left winding of meter magnet 9 to ground. The meter magnet 9 energizes in this circuit and advances the counting train 29 one step to charge the call against the calling party. In closing its front contact the meter magnet locks itself by its right winding over conductor 30 and spring 4 of the switch C to the grounded release conductor 14, to prevent a second operation of the meter for the same connection.

The squares marked 31, 32 indicate the primary and secondary master switches, but since these switches do not form any part of the present invention and their operation is well known, they need not be described.

It will thus be seen that the present invention provides a metering circuit wherein momentary reversals of the current in the trunk, as for example, in ringing back on the line in the case of revertive party line calls, or when ringing current is sent back over the line for bell adjusting purposes, the polarized relay in the trunk through which such current passes will not cause the operation of the meter magnet and thus falsely operate the counting train, because the polarized relay 11 will always restore its relay armature to the position shown after a temporary reversal before the circuit of the slow-to-release relay 10 has been opened long enough to cause its release.

It will also be apparent that the means for operating the primary and secondary line switches is an improvement upon the said Wicks patent for the reason that the operating circuit for the pull-in winding 12 of the secondary line switch is closed as soon as the primary line switch closes its contact 7. The slow relay 13 of the secondary line switch thereupon operates to ground holding conductor 21 to maintain the primary line switch set. In the said Wicks patent the circuit of the pull-in winding of the secondary line switch is not led directly through contacts of the primary line switch, but the primary line switch must first operate a relay which in turn closes the operating circuit of the pull-in winding 11 of the secondary line switch, and this relay, although fast in itself, has its complete energization delayed by the fact that its circuit includes a low resistance meter magnet.

The circuit arrangement of applicant eliminates this time interval, and shortens by that much the period between the plunging of the primary line switch and conse-

quent opening of the circuit of the line relay 2, and the placing of ground on the holding winding by relay 13 to hold the primary line switch set after the relay 2 releases.

5. What is claimed is:

1. In a telephone system, a calling line, a meter associated with said line, a circuit for extending said line, meter operating means associated with said circuit said means

10 including a relay responsive to unidirectional current flow in said circuit and means for preventing momentary operations of said relay from becoming effective to render said first means operable.

15 2. In a telephone system, a calling line, a meter associated with said line, a circuit for extending said line, meter operating means associated with said circuit, said means including a permanently polarized 75 biased relay and means for preventing momentary operations of said relay from becoming effective to render said first means operable.

20 3. In a telephone system, telephone lines, primary and secondary line switches, a meter for each of said lines, a circuit including a winding of said meter for operating said secondary line switch, means in said primary line switch for controlling said 80 circuit, said meter being constructed and arranged so as to remain unoperated upon operation of said means, and additional means for subsequently causing said meter to operate.

25 4. In a telephone system, telephone lines, primary and secondary line switches, a circuit including said switches, a meter control relay in said circuit between said switches, meters for said lines, a circuit for operating said secondary line switch including a winding of said meter, a contact of said primary line switch, a normal contact of said control relay, and the operating magnet of said secondary line switch, 85 said meter being constructed and arranged not to operate in said circuit, and means for subsequently closing an operating circuit for said meter.

30 5. In a telephone system, telephone lines, primary and secondary line switches, a meter for each line, means including a relay for operating the meter, a circuit including a winding of said meter for operating the secondary line switch, means in said primary line switch for controlling said circuit, said meter being constructed and arranged so as to remain unoperated upon operation of said last means, and means responsive to a called line in answering for causing the relay to operate said meter.

35 6. In a telephone system, telephone lines, primary and secondary line switches, meters for said lines, a meter control relay, a circuit for operating said secondary line switch including a winding of said meter

and controlled by the primary line switch, said meter being constructed and arranged not to operate when said circuit is closed, an operating circuit for said meter, means for operating said meter control relay to 70 close one point in said circuit, and means controlled by said relay for delaying the complete closure of the meter circuit by holding said circuit open at another point.

7. In a telephone system, telephone lines, primary and secondary line switches, meters for said lines, a polarized relay, a circuit for operating said secondary line switch including a winding of said meter and controlled by the primary line switch, said 75 meter being constructed arranged not to operate when said circuit is closed, means for reversing the current upon the completion of the connection to operate said polarized relay to close said meter circuit at one point, a slow relay, a circuit therefor opened when said polarized relay operates, said slow relay upon its deenergization closing said meter circuit at another point to operate the 80 meter.

8. In a telephone system, telephone lines, primary and secondary line switches, call registers for said lines, an operating magnet associated with each call register, a circuit closed by the primary line switch in operating for operating the secondary line switch, said circuit including the call register magnet of the calling line, the register magnet being constructed and arranged so 95 as to remain unoperated when said circuit is closed, and means for subsequently causing said register to operate.

9. In a telephone system, telephone lines, primary and secondary line switches, meters for said lines, a circuit including a winding 100 of said meter for operating said secondary line switch, means in said primary line switch for controlling said circuit, said meter being constructed and arranged so as to remain unoperated when said circuit is closed, and means in the primary line switch including a polarized relay for subsequently causing said meter to operate.

10. In a telephone system, telephone lines, primary and secondary line switches, a 105 meter for each line, means including a polarized relay for operating the meter, a circuit including a winding of said meter for operating the secondary line switch, means in said primary line switch for controlling said circuit, said meter being constructed and arranged so as to remain unoperated when said circuit is closed, and means responsive to a called line in answering for causing the 110 polarized relay to operate the meter.

11. In a telephone system, telephone lines, primary and secondary line switches, call registers for said lines, an operating magnet associated with each call register, a circuit closed by the primary line switch in oper- 130

ating for operating the secondary line switch, said circuit including the call register magnet of the calling line, the register magnet being constructed and arranged so as to remain unoperated when said circuit is closed, and means including a polarized relay for subsequently causing said register to operate.

12. A telephone system wherein current reversals of long duration are employed for

meter operation and current reversals of short duration are employed for other operations, characterized in this that means is provided for suppressing the effect on said meter of any reversal of short duration regardless of its current strength. 15

In witness whereof, I hereunto subscribe my name this 5th day of June A. D., 1922.

RALPH L. QUASS.
